UNITED STATES PATENT OFFICE.

SPENCER McCAY, OF GREENWICH, OHIO, ASSIGNOR TO H. J. HASKELL, OF ZANESVILLE, OHIO.

SNAP-HOOK.

SPECIFICATION forming part of Letters Patent No. 667,401, dated February 5, 1901.

Application filed February 21, 1900. Serial No. 6,091. (No model.)

To all whom it may concern:

Be it known that I, SPENCER McCAY, a citizen of the United States, residing at Greenwich, in the county of Huron and State of Ohio, have invented certain new and useful improvements in Snap-Hooks; and I do hereby declare the following to be a full, clear, and exact description of the invention, such as will enable others skilled in the art to which it appertains to make and use the same.

This invention has for its object the provision of a snap-hook of novel construction and formed of a single length of wire and which is reinforced at the attaching ends, thereby enabling the device to be made from wire of comparatively light gage consistent with the strain to be borne or sustained thereby.

The hook is free from loose and pivoted parts, cannot become accidentally loosened or detached when properly applied, is light, durable, and strong, and capable of being constructed of wrought or drawn metal, as wire, which is best adapted to withstand strain, blows, and sudden twists.

The invention also consists of the novel features, details of construction, and combination of the parts, which hereinafter will be more fully described and finally claimed, and for this purpose and also to acquire a knowledge of the merits of the invention and the structural details of the means whereby the results are attained reference is to be had to the appended description and the drawings hereto attached.

While the essential and characteristic features of the invention are necessarily susceptible of modification, still the preferred embodiment of the invention is illustrated in the accompanying drawings, in which—

Figure 1 is a perspective view of a snap-hook embodying the essence of the invention. Fig. 2 is an edge view thereof. Fig. 3 is a plan view, the dotted lines showing the hooked ends pressed apart.

Corresponding and like parts are referred to in the following description and indicated in all the views of the drawings by the same reference characters.

The device is provided at opposite ends with loops 3 and 4, respectively, the loop 3 being

designed to receive the folded portion of the strap (not shown) in the ordinary manner and the loop 4 adapted to engage with the ring or part to which the hook is to be snapped. 55 The loop 3 is approximately of D form and consists of coils arranged side by side. The loop 4 is composed of two members placed side by side and adapted to be separated to admit of the hook being engaged with or disengaged 60 from the ring or other part of a harness in the well-known manner. The side members 1 and 2, connecting the loops 3 and 4, curve in opposite directions and cross at their ends in reverse directions—that is, the member 1 65 crosses over the member 2 at the point 5 and passes beneath the member 2 at the point 6. The loop 3 and members 1 and 2 are in the same plane and the loop 4 is in a plane at a right angle to the plane of the parts 1, 2, and 70 3. The terminal portions of the members 1 and 2 are formed into hooks a and b, which curve in opposite directions and lie side by side, their terminal portions being inturned, as shown at 8 and 9, to prevent accidental 75 disengagement of the hook from the part to which it is applied. The extremities of the incurved portions 8 and 9 are inversely deflected and terminate in a point 10, which is located in line with the longitudinal center 80 of the hook. The subjacent arrangement of the hooks a and b precludes the possible casual disengagement of the device when properly positioned, and the hooks a and b mutually coöperate to sustain the strain, thereby adding 85 materially to the strength of the device in its entirety and enabling the wire from which it is formed to be of comparatively small gage.

By having the side members 1 and 2 curved 90 in opposite directions pressure brought laterally thereagainst from opposite directions brings them together and effects a separation of the loops a and b to admit of the snap-hook being engaged with a ring or other part to 95 which it is to be applied, the ring (not shown) being passed between the loops a and b and given a one-quarter turn and again drawn forward to cause it to enter the loop 4, after which the pressure is removed from the parts 100 1 and 2, when they will spring outward and close the hooks a and b and secure the part

received in the loop 4 from accidental displacement. The crossing of the side members 1 and 2 in opposite directions at the points 5 and 6 prevents displacement of the hooks *a* and *b* in a direction at a right angle to the plane of the parts 1, 2, and 3. The incurved parts 8 and 9 abut and form the point 10 and prevent movement of the hooks *a* and *b* in one direction, and the crossing 6 prevents movement of said hooks in the opposite direction. Hence they are caused to maintain a subjacent relation which is beneficial. The only movement that the hooks *a* and *b* have is laterally, or in the plane of the parts 2 and 3, so as to admit of the snap-hook being placed in position or removed as required.

The snap-hook is constructed from a single length of spring-wire of suitable gage, according to the size and load intended to be sustained by the device, and this wire is doubled upon itself at a central point and is coiled to provide the loop 3, the end portions being oppositely curved to provide the side members 1 and 2, the hooks *a* and *b*, and the incurved terminal portions 8 and 9. The reverse crossing of the side members 1 and 2 at the points 5 and 6 is essential to preserve the form and working relation of the parts. A straight line passes centrally through the loops 3 and 4 and midway between the parts 1 and 2 and touches the points of crossing 5 and 6. Hence it will be understood that the strain is evenly

distributed upon all parts of the hook when the device is in service. By having the snap-hook constructed of wire it is exceedingly light, 35 possessed of strength, and can be cheaply and economically manufactured, and the side members are adapted to be compressed so as to spread the hooks *a* and *b*, and when released said side members spring outward and 40 close the hook.

Having thus described the invention, what is claimed as new is—

As an improved article of manufacture, a snap-hook constructed of a single length of 45 wire doubled upon itself and coiled forming a strap-loop, and having the folded portions adjacent to the strap-loop crossed, thence oppositely curved in the plane of the strap-loop and again brought together and reversely 50 crossed and interlocked by a half-twist, and having the end portions oppositely and symmetrically curved to form hooks which lie side by side and form a ring-loop in a plane at a right angle to the plane of the strap-loop 55 and the connecting members, and having the terminal portions inturned and reversely deflected, substantially as described.

In testimony whereof I affix my signature in presence of two witnesses.

SPENCER McCAY. [L. S.]
